[57] CLAIM

The ornamental design for a bottle, as shown and described.

DESCRIPTION

FIG. 1 is a side elevation view of a bottle constructed in accordance with my design, the appearance of the bottle from all four sides being identical;

FIG. 2 is a bottom plan view of the bottle shown in FIG. 1;

FIG. 3 is a top plan view of the bottle shown in FIG. 1;

FIG. 4 is a side elevation view directly toward a corner panel of the bottle shown in FIG. 1;

FIG. 5 is a perspective view of the front, top and side of the bottle shown in FIG. 1; and,

FIG. 6 is a perspective view of the bottom and side of the bottle opposite that shown in FIG. 5.

The broken lines showing a bottle neck are for illustrative purposes only and do not form part of the claimed design.
